(57) **CLAIM**

We claim the ornamental design for a portion of a roller
skate, as shown and described.

DESCRIPTION

FIG. 1 is a perspective view of a portion of a roller skate,
seen from the front and right side thereof, showing our new
design;

FIG. 2 is a right side view thereof;

FIG. 3 is a left side view thereof;

FIG. 4 is a front end view thereof;

FIG. 5 is a rear end view thereof;

FIG. 6 is a top view thereof; and,

FIG. 7 is a bottom view thereof.

The broken line showing of other parts of the roller skate
shown in the drawing is for illustrative purposes only and
form no part of the claimed design.
